(57) CLAIM

The ornamental design for a key, as shown and described.

DESCRIPTION

FIG. 1 is a front left perspective view of a key constructed in accordance with the new design, including a round shaped key head and blade;

FIG. 2 is a front elevational view thereof;

FIG. 3 is a rear elevational view thereof;

FIG. 4 is a top plane view thereof;

FIG. 5 is a bottom plane view thereof;

FIG. 6 is a right side elevational view thereof;

FIG. 7 is a left side elevational view thereof; and,

FIG. 8 is an enlarged cross-sectional view taken along line 8-8 of FIG. 3.

The broken lines on the drawing views are for illustrative purposes only and form no part of the claimed design.
